UNITED STATES PATENT OFFICE

108,653

DESIGN FOR A PLUG-IN DETACHABLE, ELECTRICAL, PYROGRAPHIC, STYLUS UNIT FOR ELECTRIC PENCILS

Harry A. Ungar, Los Angeles, Calif.

Application April 10, 1937, Serial No. 68,675

Term of patent 3½ years

To all whom it may concern:

Be it known that I, Harry A. Ungar, a citizen of the United States and resident of Los Angeles, Los Angeles County, State of California, have invented a new, original, and ornamental Design for a Plug-In Detachable, Electrical, Pyrographic, Stylus Unit for Electric Pencils, of which the following is a specification, reference being had to the drawing, forming a part thereof.

Figure 1 is a side elevation of the stylus unit showing my new design.

Figure 2 is a terminal end view, and Figure 3 is a burning stylus end view of the unit.

I claim:

The ornamental design for a plug-in, detachable, electrical, pyrographic, stylus unit for electric pencils, substantially as shown.

HARRY A. UNGAR,
